THE NORRIS PETERS CO., PHOTO-LITHO., WASHINGTON, D. C.

United States Patent Office.

CHARLES WYNDHAM, OF SOUTHOVER GRANGE, NEAR LEWES, ENGLAND.

Letters Patent No. 106,529, dated August 16, 1870.

IMPROVEMENT IN VELOCIPED.

The Schedule referred to in these Letters Patent and making part of the same

To all whom it may concern:

Be it known that I, CHARLES WYNDHAM, of Southover Grange, near Lewes, in the county of Sussex, England, do hereby declare that I am in possession of an invention for "Improvements in Bicycle-Velocipedes, and in apparatus to be fitted thereto," and that the following is a full, true, and exact description thereof, reference being had to the accompanying drawing and to the figures and letters marked thereon; that is to say:

These improvements relate—

Firstly, to the construction of parts of two-wheeled vehicles or velocipedes, usually termed bicycles, for the reception of apparatus hereafter described, so that the rider obtains perfect command over the same, should he desire to stop suddenly, or otherwise.

Secondly, to means of raising or lowering a jointed or a sliding leg, strut, or bar, to keep the vehicle upright when it is at a standstill;

Thirdly, to means or apparatus for retaining the leg, strut, or bar in a raised or lowered position, or at an angle, for enabling the rider to mount and dismount without fear of the vehicle running before him;

Fourthly, to the combination of step, bar, and jointed or sliding leg in one or more pieces, at the same side or at opposite sides of the vehicle; and

Fifthly, to modifications of the above-named improvements, as hereafter described and illustrated.

In order that my invention may be thoroughly understood, I describe the several parts, in connection with the annexed drawing.

Figures 1 and 2 represent, in side and back-end view, a bicycle-velocipede, with one form of apparatus applied thereto, for retaining the vehicle in an upright position, and to enable a person to mount and dismount without fear of the vehicle running before him.

The apparatus consists of a bar, *a*, which is secured to the backbone or main frame *b* of the vehicle by pins or bolts, slightly in advance of the hind wheel *c*.

The bar carries a step, *d*, at its lower part, and terminates in a half-joint, *e*, so that a leg, *f*, can be pinned to it in a loose manner.

The leg is spread out at the bottom, to form a bearing-surface or foot to rest upon the ground, so that, when the leg is in a vertical position, as shown, the vehicle will stand upright.

I prefer to fit one bar, *a*, and leg *f*, to each side of the vehicle, as shown in fig. 2, to prevent it falling over to the right or left, and to enable a rider to mount or dismount from either side, but it is only necessary to fit them to one side. In that case it is advisable to make the leg of shorter length, to admit of

the vehicle being inclined slightly to that side, to rest the foot upon the ground.

The leg is notched or formed with ratchet-teeth at *g*, for the reception of a pawl or drop-lever, *h*, the lower end of which is looped to embrace the leg, and compel it to rise when the cord *i* is pulled up by the rider.

Above the joint I attach a spring, *j*, to bear upon the pawl, to keep the teeth in contact when the cord is free.

The cord is led over and under pulley-rollers *k l*, to guide it to the front of the vehicle, and from thence it passes up to the handle-bar *m*, where it is attached to a ring, *n*, for sliding thereon.

The socket *o* of the shear-fork has a spring claw, *p*, pinned or centered upon it, for holding the ring secure when it has been drawn along the bar *m* to raise the leg, or the handle may be fitted with a spring catch, *n'*, figs. 2^a and 2^b. This would happen when the rider has mounted the vehicle and got one foot upon one of the cranks of the front wheel, to propel the vehicle forward, as at the same instant he draws the ring along the bar to engage it under the claw, and raises the leg *f* clear of the ground.

The handle-bar is free to be turned to apply the brake in the usual manner, as the application of my improvements does not in any way interfere with the working of vehicles of the present construction.

When I fit a duplicate set of bars and legs to a vehicle, I either connect the two cords at the front, and then lead one cord only up to the ring, or I carry both ends up to the same ring, to be retained by a single claw; but I can, if I desire it, lead each cord up to separate rings, and arrange the rings at each end of the bar, so that they take under separate claws. By this means the rider can lift or lower either leg, according to the side he desires to dismount.

In the above figures I have represented the bar or bars *a* as being straight in themselves, but thrown out at an angle from the backbone, so that they form a strut, to prevent the vehicle falling over.

Now, it is not essential that they should be thrown out in that way, as the bar or bars may be carried down in a direct vertical line, and by having a bent or curved piece, *q*, as shown in Figure 3, the leg is kept out sufficiently far to form the strut.

In all cases it is necessary that the leg should be vertical, or nearly so, so that, when the weight of the rider is put upon the step *d*, a direct downward thrust is obtained.

In the foregoing description and figures I have described and shown the pawl as being acted upon by a spring, *j*, but that is not at all times necessary, as the spring may be made to act direct upon the leg *f*, as

shown at Figure 4, and the drop of the pawl shall be such that its tooth shall always engage itself into the notches or teeth of the leg when the cord is released.

Figure 5 represents a bar, *a*, and leg *f*, without a pawl or teeth. The cord *i*, in this case, is secured to an eye of the leg. The spring *j* causes the leg to move downward, as in the previous figures.

I prefer that the spring *j* shall act either upon the leg or upon the pawl, in the manner shown, but in some cases, when the pawl is loose, I fit a flat-bowed spring, *r*, to the leg, and cause it to press the loop outward, as shown in Figure 4*.

This bowed spring is used in addition to the other spring, which is of a spiral form.

The inner coil of the spiral spring is squared, to fit the square of the pin on which it is slid. By this means it is attached in an easy and secure manner.

Figures 6 and 7 represent a modified manner of attaching the cord so that it shall act upon the leg in the manner before described.

In this case I fasten the cord in the groove of a roller, and I attach the roller *s* to the spring *j*, so that, when the cord is pulled up, a partial rotation is given to the roller, and an extra strain is put upon the spring *j*.

In some cases, for the sake of adding as little weight as possible to the bicycle, when two legs are fitted, I only carry one bar, *a*, down from the back-bone *b*, and I attach the legs *f* to projecting pieces *t*. These pieces may be fixed and form part of the bar *a*, as shown in Figure 8, or they form part of the leg, as shown in Figure 9. In that case I joint the pieces *t* to the bar *a*, and I attach springs and pawls, to be acted upon by cords, as in the previous figures.

I do not confine myself to attaching the bar or bars *a* to the back-bone *b* by pins or bolts, as the bar may be retained on the back-bone by clips and a key, such as is shown at Figure 10, or a brace or saddle, as shown in Figure 11, and in some instances these modes would be advisable, as the bar could be shifted and secured at any part of the back-bone, for persons of different lengths of legs, so that the step or steps could be brought within their reach.

Another advantage to be gained by this mode would be the non-weakening of the back-bone by making holes in it, as would be the case when pins or bolts are employed, as before referred to.

In the previous description I have referred to the step *d* as being at the lower end of the bar *a*, and I have given my reasons for so making it, but, by certain modifications, I can fit two bars, *a*, on each side or only on one side of the vehicle, one to carry the step *d* and the other to carry the leg *f*, as shown at Figure 12. Of course separate step-bars and separate leg-bars can be fitted to vehicles having any of the arrangements before mentioned arranged therewith.

In some cases the step-bar might be dispensed with, or only used on one side of the vehicle, while the leg-bar is used on the other, and this would be of great advantage to some persons, as the leg-bar could always be on the side opposite to that to which the rider mounts or dismounts, for it is well known that in most cases riders can only mount or dismount from one side of the vehicle.

I have not shown a figure with the step-bar on one side of the back-bone and the leg-bar on the other, as such a fitting can be easily imagined, whether they are attached by the same pins, bolts, or clips, or otherwise.

In all the previous figures I have referred to, I have shown the step-bar or the leg-bar as being arranged at the center of the back-bone, or just in front of the hind wheel *c*. Now, this is not at all compulsory, as the bar or bars can be arranged at any other part of

the main frame, or to the shears of the front or of the hind wheel, or to some piece attached thereto.

In Figure 13 I have shown a combined step and leg-bar as being jointed to a depending piece or bar, *a*, keyed to the fork of the front wheel, *v*, of a bicycle. The bar and leg are lifted by the loop of the pawl, when the cord is drawn up, in a similar manner to the legs, as previously described; and

Figure 14 represents a similar bar and leg centered upon the axle of the front wheel, and acted upon in a corresponding manner.

The difference between these two last figures is, one of the legs is at right angles to the bar, which is horizontal, while in the other the bar is at an incline.

Figure 15 is a front view of a bicycle, with two combined step and leg-bars attached to the front axle.

It will be seen that the bars are suspended outside the shear-bearing, and inside of the cranks, so that the rotation of the cranks is not interfered with.

Figure 16 shows a pair of combined step and leg-bars arranged upon the shears or forks of the hind wheel.

The bars are connected by a transverse rod, *w*, in a loose manner, to enable one to be acted upon independently of the other. The rod determines the distance the bars shall be apart, and serves, in a great measure, for steadyng their motion.

In the arrangements shown in figs. 13 and 14, guides may be fitted for the bars to slide in, to insure them working in parallel manner.

In most of these last-mentioned figures only flat springs are shown, but other-shaped springs which will perform the required functions can be used.

In Figure 17 I have shown a combined step and leg bar jointed close up to the back-bone *b*. In this case I assist the lifting action of the pawl by a spring, *x*, so that the strain upon the rider's hand is reduced when he is pulling the cord up. I prefer, in this case, to make the pawl, so to speak, double-ended—that is, center it at or near its middle, so that the unlooped end can have the cord attached to it, as shown.

I force the tooth of the pawl into the notches or teeth of bar by the spring *j*, as in the former cases. The length of the bar and step will cause it to fall into a vertical position when the cord is released.

It is sometimes necessary to fit a small roller to the bottom of the leg, so that, should the leg touch the ground before the vehicle is fairly at a stand-still, the roller eases the drag or motion, and prevents a sudden jolt or jerk that might be given.

In this last figure I have shown a roller, *y*, to fully explain how it may be fixed.

In all the previous figures I have shown that the legs are drawn upward, or lifted in a circular direction, by the pull or action of the cord. Now, in some cases, it may be found of importance to draw down the leg by the pull or action of the cord, and this could be accomplished by carrying out an additional piece, *z*, from the front of the bar *a*, as shown at Figure 18. In this case the tendency or action of the spiral or coiled spring *j* is to lift the leg clear of the ground, instead of forcing it downward, as explained in the other figures. This plan could, however, be adapted to any or all of the previous modes, if it should be found desirable.

It will be seen that, in most of the previous figures, I have shown a special form of joint, and it is of great consequence to the successful working of the bar *a* or leg *f*, as it is essential that they should only move a fixed distance in one direction. The joint is known as the carriage-head joint, and has a lip or abutment on one-half of each of its ends, which come against each other when the leg is in a vertical position, and thereby insures the safety of the step and leg when the weight of the rider is upon it.

One or other of the notches or teeth in the bar or in the leg is engaged by the pawl at whatever angle it or they may be placed; for instance, if the vehicle stops on a portion of the road which is uneven, and the leg should rest upon a stone or other body higher than the proper level, the pawl will take into a different notch or tooth to what it would if the road were level. By this means the pawl would act as a stay or tie between its pin and the notch, and hold the leg firmly upon the higher level, so that the weight of the rider could be supported upon it with freedom.

Figures 19 and 20 represent, in side and back-end views, a bicycle fitted with another construction of legs, *f*, which can be lifted by the cord or cords *i* in the same manner as those before described.

These legs slide within guides or sockets, *a'*, on the bars *a*, and they are forced toward the ground by the weight of the rider's foot when he presses upon the step *d*, which is on the upper part of the leg, as shown.

This leg is drawn up clear of the ground by a strained spring, *j*, when the pawl *h* is released by the pull of the cord *i*.

In fig. 19 the pawl *h* only is notched, and the edge of the step *d* is caused to engage itself into one of the notches, according to the distance the leg is depressed.

The spring employed with this leg is, preferably, of vulcanized rubber, with eyes at its ends, so that it can easily be hooked over studs, as shown by the dotted lines.

It will be observed that the step *d* forms one of the sockets to guide the leg *f* up and down the bar *a*, and this is, perhaps, the best mode of fitting it, as it prevents the leg turning into such a position as to put the step *d* out of the reach of the rider's foot, or to make it inconvenient to get at; but it is not compulsory to arrange it in this manner, as two or more sockets may be on the bar or on the leg, and the spring may be fitted in any convenient manner, so that the step should be kept as near to the side as possible.

In Figure 21 I have shown a sliding leg, with the spring *j* fitted under the step *d*, and connected to it and the lower part of the leg *f*, to draw the leg down when the cord is released. These legs and bars are shown of circular shape, but they may be of square or other sectional form; or the leg may be circular, and the bar square, to act as a guide, as in Figure 21.

In Figure 22 I have shown a flat bar and a flat leg. The bar is recessed, so that the pawl *h* shall pass through, for its teeth to become engaged with the top edge of the leg *f* when it is depressed. The spring *j* is fastened to the leg, and its free end can be hooked onto its stud, to draw up the leg when the rider wishes to use the vehicle; but, when the vehicle is not in use, it is intended that the spring shall be unhooked, so that the strain is removed, to save it from injury. The leg is kept in its downward position, to retain the vehicle upright, by the pawl *h*. Sometimes I dispense with the loose pawl, and I make the notches or ratchet-teeth upon a fixed part of the bar or of the leg.

In Figure 23 I have shown a notched plate on the bar *a*, and I make the aperture in the step rather larger, so that, when the step and leg are depressed, the step is caused to take into one or other of the notches by a backward or forward action of the foot at the time of depressing it.

When it is necessary that the leg should be raised, the step is moved either backward or forward by the cord *i*, to release it from the notch, when the spring *j* will cause it to slide up the bar.

I have referred to the employment of rubber, or spiral, or coiled springs, or of flat springs, for acting upon the sliding legs; but I do not limit myself to their use, as in some cases helical springs may be used; and in

bar, and having for its abutments the socket *a'* and the step *d*. This figure shows no means of retaining the step *d* in a downward position, and, with expert and bold velocipedists, this would be preferred, as the instant the rider's foot is removed from the step, the leg springs up the bar by itself. With some riders, it will be necessary to provide means of drawing up the leg by hand, and that may be accomplished by means of the cord *i*.

There are many ways of retaining the leg in a downward position, either when draw-up springs are fitted, or when the legs are not provided with springs, such as would be the case when the leg is heavy enough to fall by its own weight, as in the one represented in Figure 24.

In Figure 25 I have shown the socket as being fitted with a thumb-screw, *a'*, the tightening up of which pinches or bites against the bar with sufficient force to hold the leg secure.

I do not confine myself to the depth of the socket, nor to the employment of two or more of them, as in many cases it will be found only necessary to have one, and that of such a length that the leg shall be steadied in its movements.

In Figure 26 I have shown a socket, *a'*, of great depth, with the step *d* attached to it.

The socket is provided with a thumb-screw, as in the previous figure, and can be drawn up when released automatically by the spring *j*.

The leg may be drawn up by means of an additional cord, *i*, attached to the pawl, and the pawl may be returned to position by a flat spring, or by a coiled spring, as shown in figs. 21 and 28.

In some cases it would be advisable to dispense with the thumb-screw or screws, on account of the time it would occupy to turn and secure them, and in their stead pins or wedges could be used which are of easy adjustment.

In Figure 29 I have shown a pin, *j'*, passed into a hole in the bar, and above the step, so that the leg is prevented rising while the pin is in the hole.

The pin is attached to the free end of the rubber spring *j*, so that the spring is of double utility, viz: that of a pin-holder when it is unhooked from the stud, and of a spring when it is hooked.

Figure 29^a represents the pin in the leg.

In Figure 30 I have shown such a pin passed into a hole through both the socket and bar.

When I use a wedge, I prefer to attach it to the spring, as shown in Figure 31, and insert it into a hole made for its reception at the back or side of the step. It is forced in with sufficient pressure to hold the leg firm when a plain leg is used, but when a notched leg or a notched bar is employed, it will only be necessary to drop it into the hole to compel the step or some other part to take into one or other of the notches.

In cases when the bar and the leg are made of very thin metal, I connect a stay or tie-rod, *c*, from the bar to the frame in any convenient manner.

In the case of fitting a bar to the back-bone, I clip or bolt the tie-rod in place, as shown at fig. 23.

In the foregoing description, I have described the cord *i* as being connected to a ring, *n*, to slide upon the handle bar *m*, but I do not restrict myself solely to that mode of drawing up or letting down the leg or legs, as I can employ a sheave on the handle-bar *m*, or on an additional bar close to one or other of the handles.

In fig. 20 I have shown a sheave, *A*, connected with a tube, *B*, and a collar or washer, *C*, to form one piece.

The length of the tube is such that the sheave is put directly over the pulley-roller *L*, to prevent the cord being drawn out of the groove, and to serve as a means of steadyng the sheave in its rotation.

Figure 24 I have shown such a spring encircling the

The collar or washer C is formed with about four ratchet-teeth on its periphery, and a projecting button or thumb-piece, D, so that when the button is lifted by the rider's thumb or finger, the sheave is caused to rotate a given distance either to draw up or release the leg.

The ratchet-teeth are engaged by a spring pawl, E, and holds the sheave in the position to which it was moved.

The button is attached to a bent piece, as shown, to bring it within reach of the rider's thumb or finger, without releasing his hold upon the handle.

The tube may be dispensed, and the collar or washer D may be connected to the sheave by distancing pieces or rods F F, as shown in the detached view, Figure 32.

The diameter of the sheave is such that an eighth of a revolution will be sufficient to act upon the cord and leg or legs.

The spring pawl E is bent over to the inside of the collar D, to act as a stop to prevent it moving from its proper place.

Sometimes I make the handle bar in two pieces, and so arrange it that the turning of one handle shall rotate the sheave, and the turning of the other handle shall draw up or release the break. This is represented in Figure 33.

It consists in carrying up a bracket, G, from the handle fork, and leading the inner ends of both bars m and m' into one arm of the bracket to hold both bars in place.

The bar m' is prevented leaving the bracket arms G by the split-key I.

Before concluding I desire it to be understood that any one part of my invention may be used in connection with any other part or parts, either with the jointed leg or legs, jointed bar or bars, or with the sliding leg or legs, and whether one system or part

thereof be used with the other system, or at part of the same in any way.

Having thus explained and shown the nature of my invention, and the manner of carrying the same into execution,

I desire to claim—

1. The construction and employment to bicycles of a jointed leg or legs, bars or struts, which is or are capable of being drawn up or down by a cord or cords, in the manner and for the purposes hereinbefore described and shown.

2. The spring claw or catch upon the handle or handle bar, for retaining the cord and leg, or bars and legs, in a raised or lowered position, in the manner described and illustrated.

3. The construction and employment of a sliding leg, whether such leg be fitted with a pawl-rack or other appliance for retaining it in a raised or lowered position, in the manner and for the purposes before described and shown in the drawing.

4. The sheave or sheaves, and the parts connected therewith, for drawing up the cord or cords of the jointed or sliding leg or legs, as hereinbefore described and represented in the drawing.

5. The employment of a pawl or a spring or a pawl and a spring, to return the leg or legs or bars into the reverse position, as hereinbefore described and represented in the several figures of the drawing annexed.

In witness whereof, I, the said CHARLES WYNDHAM, have hereunto set my hand this 21st day of April, 1870.

C. WYNDHAM.
